HANDBAG FRAME

Filed Nov. 6, 1947

UNITED STATES PATENT OFFICE

2,556,874

HANDBAG FRAME

Salvatore Giordano, Forest Hills, N. Y.

Application November 6, 1947, Serial No. 784,338

2 Claims. (Cl. 150—29)

1

This invention relates to handbag frames such as are used in the manufacture of women's handbags.

It is the object of this invention to provide a tubular handbag frame comprising a pair of frame members with tubular outer portions and which are mirror images of each other, having novel structural features.

These and other advantageous objects, which will appear from the drawings and description hereinafter, are illustrated in the drawings, embodying a practical form of the invention, wherein:

Fig. 1 is a fragmentary, perspective view of a handbag embodying a frame of my invention,

Fig. 2 is an elevational, fragmentary, vertical sectional view thereof, taken on line 2—2 of Fig. 1,

Fig. 3 is an end elevational view thereof, taken on line 3—3 of Fig. 1,

Fig. 4 is a perspective view of the frame member, partly broken, and

Fig. 5 is a fragmentary, side elevational view of a handbag having a frame embodying my invention.

As shown in the drawings, the tubular frame embodying my invention comprises the frame sections 10, 10' which are mirror images of each other. For the sake of simplicity, the reference numbers of frame section 10 with prime marks added thereto have been used with regard to the corresponding parts of frame section 10.

The tubular frame section 10 is provided with a bagging channel member 11 medially pendent therefrom and outwardly offset from the line 18 which marks the meeting point of the frame sections 10, 10' when in their closed position (as shown in Fig. 2). The channel 11 is the bagging portion of the frame section and comprises a relatively long inner wall 12, which is substantially aligned with the longitudinal center of the tubular frame 10 and is pendent therefrom, and an outer wall 14 of lesser height than the inner wall 12 spaced therefrom and connected thereto by the edge portion 13. The free edge 15 of the outer wall 14 defines, with the frame section 10, and the inner wall 12, a pocket 16 for the reception of the handbag material 17 which may be clamped therein between walls 12, 14 of bagging channel 11, or secured to said channel in any other desired or convenient manner.

By this arrangement, tubular frame sections 10, 10' when in closed position, will be in continuous longitudinal abutment at 18, with the bagging channels 11, 11' united to the lower ends

10

2

of the frame sections and pendent therefrom at positions offset outwardly of the point of abutment 18. Frame section 10 is slotted as at 19 adjacent the free outer end thereof. The free ends 20, 20' of the frame sections are directed toward each other in overlapping relation, with a rivet 21 passed therethrough or otherwise secured together, see Figs. 1 and 3, pivotally securing the frame sections together at their outer ends.

The channels 11 may be provided with corner reinforcing means, such as the reinforcing tab 22 shown in Fig. 4. The frame sections may be provided with any desired or convenient interengaging latch means, such as knobs 23 conventionally illustrated in dotted lines in Fig. 5, or with any other suitable or desired interengaging means.

While the frame sections 10, 10' have been illustrated in the drawings as being of generally circular cross-section, such illustration is only for the purpose of exemplifying a practical application of the invention; said frame sections may be of any desired non-circular cross-section.

It will be noted that by the invention described, it is possible to compress and distort the channel portion 11 of the frame members in bagging the material 17 to any desired degree, without altering the true lines of the tubular frames 10, 10'. Thus, the bag frame members will be of standard symmetry and beauty, and the handbag material 17 appears to be held directly within and pendent from the tubular frame. This end, as above noted, is attained by the novel structural features of the frame members 10, 10'. The bag frame is sturdy and durable; the finished bag incorporating the same is of standard neat and finished appearance, and of exceptional strength.

Having thus described my invention, what I claim as new and desire to secure by Letters Patent, is:

1. A handbag frame comprising a pair of frame sections, each section being of unitary construction and comprising a tubular main body portion which is exposed in the completed bag, and a bagging channel member integral with and medially pendent from one side of said body portion which is concealed in the completed bag, each frame section bagging channel member comprising a relatively long inner wall and an outer wall of less height than the inner wall and an edge portion of substantially lesser length than half of the thickness of said tubular main body portion, said edge portion connecting the walls

50

55

together in spaced relation to define therewith a pocket opening beneath the tubular main body portion for the reception of handbag material to be clamped in said pocket, said tubular body portions being so proportioned as to extend substantially past the edge portions of the bagging channel members so as to be in substantial alignment with the bag material positioned in the channels in the completed bag, said frame sections having leg portions and free ends on said leg portions directed toward each other in overlapping relation at right angles to the axial plane of the leg portions and pivotally secured together in that position, each free end being integral with and extending from the side of said tubular main body portion opposite that forming said bagging channel member.

2. A handbag frame as set forth in claim 1, said leg portions being slotted at their ends and being bent past said slots out of their tubular

5 cross-sectional plane to define said free ends of flat form.

SALVATORE GIORDANO.
